PROCESS FOR CRACKING OILS

Original Filed Aug. 20, 1920

UNITED STATES PATENT OFFICE.

JOSEPH G. ALTHER, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR CRACKING OILS.

Application filed August 20, 1920, Serial No. 404,745. Renewed June 9, 1926.

This invention relates to improvements in process for cracking oils and refers more particularly to that adapted for the production of gasoline or gasoline like bodies from 5 heavier oils such for example as fuel oil or gas oil cuts from crude petroleum.

Among the objects of the invention are to provide a process in which there is a maximum heating surface relative to the volume 10 of oil under treatment; to provide a process in which the flow of the oil is slowest at the hottest point, namely, in the lower part of the combustion chamber and is fastest at the cooler points, namely at the upper part of 15 the combustion chamber; to provide a process in which the oil is maintained in a larger stream and flows slower where the greatest heat transfer takes place so as to get a maximum thermal efficiency; to provide a process 20 in which the volume of oil in the stream decreases and the velocity of the oil in the stream increases as the stream passes towards the coolest part of the combustion chamber; to provide a process in which the oil may be 25 vaporized under a decreased pressure relative to the pressure in the heating chamber; to provide a process in which the reflux condensate may be returned to the system for further treatment; to provide a novel form of 30 apparatus for carrying out my process and in general to provide a novel form of process and apparatus of the character referred to.

In the drawings, the single figure shows a view with parts in side elevation and parts 35 in vertical section and parts in dotted lines of my improved apparatus.

Referring to the drawings, 1 designates a furnace having burner 2, bridge walls 3, flue 4, stack 5 and combustion chamber 6. In 40 the fire box is mounted heating chamber which takes the form of heating coils 7 connected in series to form, in effect, one continuous coil. The inlet side of the heating coil is connected to feed line 8 having control valve 9 and leading to charging pump 10 connected to any suitable source of raw oil supply. The outlet side of the heating coil is provided with transfer line 11 having control valve 12 and connected to vapor 45 chamber 13. This vapor chamber 13 is provided with residue draw-off line 14 having control valve 15 and with vapor outlet 16 leading to goose-neck 17. A valve 18 is interposed in the pipe 16 as shown. The 50 goose-neck 17 leads to the bottom of dephleg- 55

mator 19. This dephlegmator is provided with baffling material 20 and is provided at its lower end with a reflux condensate return line 21 leading to the pump 10. A valve 22 is interposed in line 21. The reflux line 60 21 is also provided with a second line 23 having control valve 24 which line 23 leads to any suitable receptacle. By this arrangement the reflux condensate need not be returned to the heating chamber for further 65 treatment. The upper part of the dephlegmator is provided with vapor outlet line 25 leading to water condenser coil 26 which in turn is connected by 27 to receiver 28. The receiver 28 is provided with pressure gauge 70 29 and liquid level gauge 30. This receiver also has liquid draw-off pipe 31 having throttle valve 32 and gas outlet valve 33 having throttle valve 34.

If desired, raw oil may be fed into the upper part of the dephlegmator by means of the pipe 35 having control valve 36. In this case the pump 10 is not connected to any other source of supply and the preheated raw oil mixed with the reflux condensate passes down 80 through the pipe 21 to the pump 10.

If desired, a differential pressure may be maintained on the system by suitably controlling valves 12 and 18 and if desired a throttle valve 37 may be interposed in the 85 line 25. Where a lower pressure is maintained on the vapor chamber and dephlegmator than the heating coils, either the reflux condensate will have to be diverted elsewhere by closing valve 22 and opening valve 90 24 or else a pump will have to be interposed in line 21. In such case the raw oil may be fed directly to the pump 10 and the valve 36 closed.

As a feature of the invention the heating 95 coils are progressively decreasing in size; for example, if there are 10 tubes to the coil, the first tube may be 6½ inches and the succeeding tubes decrease as follows as to their internal diameter: 5¾ inches, 5¼ inches, 4¾ inches, 4½ inches, 3¾ inches, 3¼ inches, 2¾ inches, 2½ inches and 1¾ inches. By means of this arrangement it will be seen that the velocity of the oil through the heating coil gradually increases. It is particularly desirable that the oil be maintained in a liquid phase during its passage through the heating coil so as to prevent precipitation of carbon in the coil and consequent clogging up or 100 burning out of the coil.

The following illustrative run may be given: Oklahoma gas oil of say 33° Baumé may be heated to a temperature of 700° F. in the heating coil and maintained under a pressure of 125 lbs. The same pressure may be maintained throughout the system and the reflux condensate and raw oil fed through the line 21 to the heating coil. This will convert 50 to 60% of the raw oil into pressure distillate of 52° Baumé and produce, based on the amount of raw oil charged, 35% of 400 F. endpoint gasoline. If desired by regulating valve 12 the pressure in the vapor chamber, dephlegmator and water condenser may be reduced to 50 lbs., or if desired a pressure of 150 lbs. may be maintained on the heating coil, 100 lbs. on the vapor chamber and 75 lbs. in the dephlegmator.

I claim as my invention:

- 20 1. The process of cracking petroleum oil, which consists in passing oil in a stream of progressively decreasing size, through a heating zone of progressively decreasing temperature, in transferring the oil while in the smallest stream to a vapor chamber, and in removing vapors from said chamber.
- 25 2. The process of cracking petroleum oil, comprising passing the oil through a coil of progressively decreasing size disposed within a heating zone wherein the diameter of the coil decreases in accordance with a lowering temperature in the heating zone, in discharging

ing the oil from the smallest portion of the coil into a vapor chamber, in collecting vapors from said chamber and in subjecting said vapors to a condensing action.

3. The process of cracking petroleum oil, comprising passing the oil in a small stream of progressively decreasing size through a heating stage wherein the highest temperature is applied to the largest stream of oil, and the velocity of the oil increased as the stream decreases, in discharging the oil into a vapor chamber, and in removing and condensing vapors from said chamber.

4. The process of cracking petroleum oil, which consists in passing the oil in a small stream of progressively decreasing size through a heating stage wherein the stream decreases in diameter and increases in velocity as the temperature within the heating chamber lowers, in discharging the oil into a vapor chamber, and in collecting and condensing vapors from said chamber.

5. The process of treating petroleum oils, which consists in slowly passing oil in a stream through the hottest portion of a heating chamber, and in gradually decreasing the size of the stream as the temperature in the chamber lowers to cause an increase in the velocity of the oil, in collecting the oil in the vapor chamber, and in discharging the vapors from said chamber for condensation and collection.

JOSEPH G. ALTHER.
